UNITED STATES PATENT OFFICE

157,068

LAMP STANDARD

Morris N. Miller, Inglewood, Calif.

Application March 28, 1949, Serial No. 1,671

Term of patent 7 years

(Cl. D48—20)

To all whom it may concern:

Be it known that I, Morris N. Miller, a citizen of the United States, residing at Inglewood, in the county of Los Angeles and State of California, have invented a new, original, and ornamental Design for a Lamp Standard, of which the following is a specification, reference being had to the accompanying drawing, forming part thereof.

The single drawing figure is a perspective view of a lamp standard, showing my new design.

I claim:

The ornamental design for a lamp standard, as shown.
